[57] CLAIM

The ornamental design for an attachable vehicle hand
brake lock, as shown and described.

DESCRIPTION

FIG. 1 is a perspective view of an attachable vehicle
hand brake lock;

FIG. 2 is a top plan view of the invention;

FIG. 3 is a right side elevational view of the invention;

FIG. 4 is a bottom plan view of the invention;

FIG. 5 is a front elevational view of the invention; and,

FIG. 6 is a rear elevational view of the invention.

The broken-line disclosure of a portion of a handbrake
in the views is for illustrative purposes only and forms
no part of the claimed design.
